UNITED STATES PATENT OFFICE.

EDWARD G. CARR, OF OCEANSIDE, CALIFORNIA.

CONCRETE-TAMPER.

1,203,482.

Specification of Letters Patent. Patented Oct. 31, 1916.

Application filed December 9, 1914. Serial No. 876,262.

To all whom it may concern:

Be it known that I, EDWARD G. CARR, a citizen of the United States, and a resident of Oceanside, in the county of San Diego and State of California, have invented an Improvement in Concrete-Tamper, of which the following is a specification.

My invention relates to improvements in tampers used in constructing concrete roads or beds and has for its object to utilize the vibrations of a gas engine or similar motor and communicate such vibrations to the tamper, with a view to rendering the tamping operation on a road more uniform and certain.

With these and other objects in view, my invention consists in its broadest aspect in the utilization of the vibrations of a motor to tamp or float a concrete road or bed.

My invention consists further in certain particular features of construction, arrangement and combination of parts as will be hereinafter fully described and pointed out in the claims, reference being had to the accompanying drawing in which—

Figure 1 is a plan view of the invention in use. Fig. 2 is a side elevation of the same. Fig. 3 is a front elevation as in use. Fig. 4 is a detail front elevation.

In carrying out my invention a carriage consisting of the axle A carrying the wheels B is used to run on the usual tracks C placed at the side of the road and defining the width thereof; on the axle of the carriage are pivoted the handles D at E, as shown in Figs. 1 and 2; the handles D it will be noticed are pivoted to the axle inside the wheels, thence extending forwardly and upwardly, as shown in Fig. 2; the tamping bar or frame F is a box-like structure consisting of the spaced apart side timbers F' and the bottom board F², the ends of the timbers F' extending beyond the tracks C as at F².

As stated the handles D are pivoted to the axles A and E and extend forwardly; near each end of the tamping frame short vertical rods or pins G are secured passing upwardly through the handles D which are horizontal at this point and thence through the triangular bracket H bolted to the side timbers of the tamping frame, the brackets also forming guides for the rods and serving to confine a coil spring l bearing downwardly on the flat portion D' of the handles, so that

the handles and tamping frame may have a flexible relative up and down motion.

At the center of the tamping frame is mounted a gasolene engine or like motor J having a fly wheel K, said wheel having the counterbalance weight K' located on the same side of the crank of the crank shaft L of the engine. The throttle or speeding mechanism of the engine is controlled by a lever M having attached to it the rod, chain or wire M' which extends to one side and is guided along one handle D and then passes into the handle which is preferably hollow or tubular to a point adjacent the hand grips D² where it can be manipulated by an operator. The motor J can be a gasolene engine, an electric motor or any suitable motor which will impart a great number of revolutions to the fly wheel so that vertical or other vibrations are set up.

To operate the device it is placed on the wooden tracks or ways C over the concrete bed and the engine started, a man being at each side and moving the device along, backward or forward by the handles D². As the fly wheel attains a high number of revolutions the balance weight K' being located on the same side as the crank shaft L it will be understood that at each revolution said weight being lifted at the same time and in unison with the crank of the shaft, that as it goes down rapidly it will impart a downwardly pounding motion to the engine and as it is rigidly secured to the tamping frame said frame will have imparted to itself a pounding motion or vibrations, these vibrations being made possible by its flexible suspension from the handles D and the truck member by virtue of the springs l interposed between the handles at D' and the brackets H which are rigidly attached to the tamping frame, as shown. To save it from the jar of the tamper the engine or motor, may, if desired or found expedient, be located directly on the truck and suitably geared up with a revolving counter weight eccentrically and rigidly mounted on a shaft on the tamping frame so that rapid revolutions of the said counterweighted shaft through the eccentricity of the weight will cause an up and down motion or vibration to the tamping frame. It has been found by this method of tamping concrete by the vibration of an engine or counterweight shaft, that the work can be done expediti-

ously, efficiently and with great uniformity of finish, the tamper striking off the concrete to a certain level and finishing the top surface by working the water up to the top. Furthermore two weights revolving in opposite directions may be used to regulate the direction of the stroke.

I claim:

1. In a concrete tamper the combination 10 with a horizontal tamping bar or frame, means for suspending the frame across and slightly above a road or bed and permitting freely a backward and forward movement of the frame and motor means carried by 15 the bar or frame for imparting vibrations to said bar or frame.
2. In a concrete tamper the combination 20 with a horizontal tamping bar or frame, means at each side of said bar or frame for suspending same across and slightly above a road or bed and permit a free back and forth motion of the frame thereover, a motor having rapid vibrations mounted on said bar or frame adapted to impart and 25 translate its vibrations to the said bar or frame and transfer said vibrations to the road or bed.
3. In a concrete tamper, the combination 30 with a horizontal tamping bar or frame, means for movably suspending the same across a road or bed slightly above the same and a motor having rapid vibration mounted on said bar intermediate its ends.
4. In a concrete tamper the combination 35 with a wheeled truck adapted to travel along a road or bed, hand bars mounted on said truck and extending forwardly therefrom, a tamping bar or frame suspended from said hand bars, a motor having a weighted fly 40 wheel and rigidly mounted on said bar or frame, whereby the vibrations of the motor are translated to the tamping bar or frame.
5. In a concrete tamper, the combination 45 with a horizontal tamping bar or frame, means for elastically suspending the same

across a road or bed, and means carried by said bar or frame for imparting rapid vibrations to the same.

6. In a concrete tamper the combination 50 with a truck, handles extending forwardly from the same, a tamping bar or frame flexibly suspended from said handles and an engine or motor rigidly mounted on said bar or frame whereby the vibrations of said engine are translated to the tamping bar to 55 impart thereto a rapid up and down motion.

7. In a concrete tamper the combination 60 with a wheeled truck adapted to travel along a road or bed, handles mounted on said truck and extending forwardly, a tamping 65 bar or frame flexibly suspended from said handles, a motor having a weighted fly wheel and rigidly mounted on said bar or frame and means mounted on one of said handles for controlling the operation of said motor.

8. In a concrete tamper, the combination 70 with a wheeled truck adapted to travel along a road or bed, handles mounted on said truck and extending forwardly, a tamping 75 bar or frame in advance of said truck, pins or rods adjacent each end of said tamping bar or frame extending upwardly through the aforesaid handles, brackets secured to the tamping bar and projecting over the 80 handles to receive the upper ends of the pins or rods, cushion springs mounted on said pins or rods between the handles and the brackets, an engine having a weighted balance wheel and rigidly mounted on the 85 tamping bar or frame intermediate its ends, whereby vertical vibrations of the engine are imparted to the tamping bar or frame and it is given a rapid cushioned up and down movement.
